Inventor:
John F. Lindberg
By A. L. Gragg Atty.

UNITED STATES PATENT OFFICE.

JOHN F. LINDBERG, OF CHICAGO, ILLINOIS.

RHEOSTAT.

Application filed May 29, 1922. Serial No. 564,307.

To all whom it may concern:

Be it known that I, JOHN F. LINDBERG, citizen of the United States, residing at Chicago, in the county of Cook and State 5 of Illinois, have invented a certain new and useful Improvement in Rheostats, of which the following is a full, clear, concise, and exact description.

My invention relates to rheostats wherein 10 the resistance is varied smoothly as distinguished from step by step variation thereof. The rheostat of my invention includes a plurality of resistance wires, and a current conducting brush preferably in the form of 15 a metallic block that bridges said wires, the brush and wires being relatively movable to shift the brush longitudinally of the wires. There is preferably, a carrier for the brush, and a spring upon the carrier 20 for pressing the brush upon the wires.

In the preferred embodiment of the invention two parallel wires are wound upon the curved surface of a cylindrical drum which carries two binding posts, one for one end 25 of each wire, the other ends of the wires being dead ended. The brush is mounted upon an adjusting arm that is concentric with the drum, said arm carrying a spring that presses the brush radially inward upon 30 both wires, the brush thus serving as a circuit closer.

The invention will be more fully explained by reference to the accompanying drawing in which Fig. 1 is a side view of a rheostat 35 made in accordance with the preferred embodiment of the invention, a form of circuit being diagrammatically illustrated; Fig. 2 is a sectional view on line 2-2 of Fig. 1; Fig. 3 is a plan view; and Fig. 4 40 is a perspective view of the brush and the arm carrying the same.

Like parts are indicated by similar characters of reference throughout the different figures.

45 The cylindrical mounting drum 1 has a base projection 2 which carries the binding posts 3 and 4 and is provided with holes 5 and 6 through which attaching screws may be passed.

50 Two uncovered resistance wires 7 and 8 are wound upon the cylindrical surface of the drum, these wires being preferably parallel and disposed in planes that are perpendicular to the axis of the drum. One of 55 these wires terminates at one end in the

binding post 3 and the other at the other end in the binding post 4. A metallic bearing sleeve 13 is co-axial with the drum and in it a shaft 14 is mounted to turn, this shaft being provided with a turning knob 15 at one end. The other end of the shaft is formed with a threaded bore to receive the stem of a bolt 16 which also passes through a hole 17 in a switch arm 18. The bolt head 19 holds the switch arm in assembly with the shaft 14 and prevents this shaft from moving toward the knob side of the drum. Any means may be provided to prevent the shaft from moving toward the arm side of the drum, the thickening of the shaft being illustrated for this purpose.

The arm 18 is desirably formed of a piece of sheet metal that bulges away from the drum as indicated at 20 and is angularly extended to overlie the cylindrical surface of the drum, is indicated at 21. The sides of the arm are closely approached so as to afford a slideway therein for the mounting brush or block 22 that is preferably of metal. A spring 23, preferably of resilient wire, is anchored at one end to the portion of the arm which overlies the flat side of the drum, this wire being continued through the hollow interior of the arm and thence outwardly to engage the outer end of the block 22, the spring serving to press the block against the wires.

The circuit illustrated in Fig. 1 includes an incandescent lamp 26, a battery 27, the contacting block or brush 22 and the portions of the wires 7 and 8 that are between this block and the binding posts 3 and 4, the balance of the wires being out of circuit. The portion of the wires that are between the block 22 and the binding posts 90 terminate in the resistance that is supplied to the lamp circuit to regulate the brilliance or heating effect of the lamp.

The rheostat of my invention is of particular service for regulating the flow of current through the filament of an audion bulb, though the invention is not to be limited to any particular use to which it may be put. The main advantage in the rheostat, as illustrated, is that the circuit which includes the resistance wires is not established through the contact arm or other moving parts except the block 22 so that no uncontrollable resistance such as that due to loose joints can enter the circuit, a feature of 105 110

much importance in the regulation of the resistance in the filament circuit of an audion bulb.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

1. A rheostat including a cylindrical mounting drum; two binding posts upon the drum; two resistance wires disposed upon the cylindrical surface of the drum, each having a binding post individual thereto and connected therewith; an arm having one portion facing a flat side of the drum and an angular portion overlying the cylindrical surface of the drum, said arm and drum being relatively rotatable upon the axis of the drum; a contacting block slidably mounted upon the angular portion of the arm and engaging both of said wires in the various positions of said arm; and a spring carried by the arm and pressing radially outward upon said block to maintain it in engagement with the resistance wires.

inward upon said block to maintain it in engagement with the resistance wires.

2. A rheostat including a cylindrical mounting drum; two resistance wires disposed upon the cylindrical surface of the drum; an arm having one portion facing a flat side of the drum and an angular portion overlying the cylindrical surface of the drum, said arm and drum being relatively rotatable upon the axis of the drum; a contacting block slidably mounted upon the angular portion of the arm and engaging both of said wires in the various positions of said arm; and a spring carried by the arm and pressing radially inward upon said block to maintain it in engagement with the resistance wires.

3. A rheostat including a cylindrical mounting drum; two resistance wires disposed upon the cylindrical surface of the drum; and an arm carrying a contact engaging both of said wires, said arm and drum being relatively rotatable upon the axis of the drum.

In witness whereof, I hereunto subscribe my name this 20th day of May, A. D. 1922.

JOHN F. LINDBERG.
